SILICON SOLAR CELL

Toshinobu Matsutani, Osaka, Japan, assignor to Sharp
Kabushiki Kaisha (Sharp Corporation)

Filed July 26, 1974, Ser. No. 492,256

Claims priority, application Japan Feb. 1, 1974

Term of patent 14 years

Int. Cl. D13—02

U.S. Cl. D26—1 R

FIG.—1

FIG.—2

FIG.—3

FIG.—4

FIG.—5

FIG.—6

FIG.—7

FIG. 1 is a front perspective view of a silicon solar cell in an operating state showing my new design;

FIG. 2 is a plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom view thereof.

I claim:

The ornamental design for a silicon solar cell, as shown.
